Primary Examiner — Jeffrey D Asch(74) *Attorney, Agent, or Firm* — Morgan, Lewis & Bockius LLP(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof including non-claimed subject matter shown in broken lines.

The broken lines in FIG. 8 are directed to non-claimed display features; the broken lines form no part of the claimed design.

1 Claim, 7 Drawing Sheets(56)
